(57) CLAIM

The ornamental design for a waistband-mounted pouch, as shown and described.

DESCRIPTION

FIG. 1 is a perspective view of the rear of a waistband-mounted pouch, showing my new design;

FIG. 2 is a side elevational view, thereof, the opposite side elevational view being a mirror image, thereof;

FIG. 3 is a rear elevational view, thereof;

FIG. 4 is a top plan view, thereof;

FIG. 5 is a front elevational view, thereof;

FIG. 6 is a bottom plan view, thereof; and,

FIG. 7 is a left front perspective view, thereof, the broken-line representations of the waistband and the gemstone array on the clip being included solely for illustrative purposes, forming no part of the claimed design;

FIG. 8 is a perspective view of the rear of an alternative embodiment, thereof;

FIG. 9 is a side elevational view, thereof, the opposite side elevational view being a mirror image, thereof;

FIG. 10 is a rear elevational view, thereof;

FIG. 11 is a top plan view, thereof;

FIG. 12 is a front elevational view, thereof;

FIG. 13 is a bottom plan view, thereof; and,

FIG. 14 is a left front perspective view, thereof, the broken-line representations of the waistband and the gemstone array on the clip being included solely for illustrative purposes, forming no part of the claimed design.
